CARRYING CASE FOR TRANSPARENCIES
OR SIMILAR ARTICLE

Robert E. Dustin, Newton, Mass., assignor to Milprint,
Inc., Milwaukee, Wis., a corporation of Delaware

Filed Oct. 4, 1967, Ser. No. 8,860

Term of patent 14 years

(Cl. D87—5)

FIG. 1 is a front perspective view of a carrying case or transparencies or similar article showing my new design; and

FIG. 2 is a rear perspective view of the carrying case for transparencies or similar article in a partially open condition showing the side and end opposite from the side and end shown in FIG. 1.

The dominant features of my design reside in the portions shown in full line in the drawings, a conventional base member being shown in broken lines. The two halves of the handle portion of the carrying case are symmetrical.

I claim:

The ornamental design for a carrying case for transparencies or similar article, as shown and described.
